Primary Examiner — Cynthia Ramirez*Assistant Examiner* — Tamara L Hahn(74) *Attorney, Agent, or Firm* — Andrew C. Cheng(57) **CLAIM**

The ornamental design for pallet truck, as shown and described.

DESCRIPTION

1.1 is a perspective view of a pallet truck showing my new design;

1.2 is a front view thereof;

1.3 is a rear view thereof;

1.4 is a right side view thereof;

1.5 is a left side view thereof;

1.6 is a top view thereof;

1.7 is a bottom view thereof;

1.8 is an enlarged view of the encircled portion labeled as **8** in 1.1; and,1.9 is an enlarged view of the encircled portion labeled as **9** in 1.1.

The broken lines in the drawings depict portions of the pallet truck that form no part of the claimed design. The dot-dash broken lines in the drawings depict enlarged portions that for no part of the claimed design.

1 Claim, 9 Drawing Sheets(56)
